(57) **CLAIM**

(21) Appl. No.: **29/218,947**

The ornamental design for a wrist rest for pulse wave
measuring instrument, as shown and described.

(22) Filed: **Dec. 10, 2004**

(30) **Foreign Application Priority Data**

DESCRIPTION

Jun. 11, 2004 (JP) 2004-017442
Jun. 11, 2004 (JP) 2004-017443

FIG. 1 is a perspective view of a wrist rest for pulse wave
measuring instrument showing our new design;

(51) **LOC (8) Cl.** **24-02**

FIG. 2 is a front elevational view thereof; the rear elevational
view being a mirror image of the front elevational
view and therefore not illustrated;

(52) **U.S. Cl.** **D24/186**

FIG. 3 is a top plan view thereof;

(58) **Field of Classification Search** D24/165,

FIG. 4 is a right side elevational view thereof; and,

D24/186, 183; 600/502, 503, 499, 494, 490,

FIG. 5 is a left side elevational view thereof.

600/485, 500, 492, 480, 493, 495, 479; 128/900
See application file for complete search history.

The broken lines are shown in the views for illustrative
purposes only, and form no part of the claimed invention.
